UNITED STATES PATENT OFFICE.

EDSON F. GALLAUDET, OF NORWICH, CONNECTICUT.

DESIGN FOR A HYDROAEROPLANE-BODY.

44,168.

Specification for Design.

Patented June 10, 1913.

Application filed May 9, 1912. Serial No. 696,239. Term of patent 14 years.

To all whom it may concern:

Be it known that I, EDSON F. GALLAUDET, a citizen of the United States, residing in the town of Norwich, county of New London, and State of Connecticut, have invented a new, original, and ornamental Design for a Hydroaeroplane-Body, of which the following is a specification, reference being had to the accompanying drawings, forming part thereof.

This design comprises an elongated body of substantially fish or torpedo shape the bottom of which, substantially flat transversely, extends downwardly and rearwardly from its nose to a point somewhat short of its longitudinal center at which point it is carried upwardly at a sharp angle for a short distance and then, forming a

reentrant angle, extends rearwardly to the tail. The running gear, comprising two wheels arranged on opposite sides of the body, is mounted within the body forward of the notch in the bottom so that less than half of the wheels project below the bottom, and a flange downwardly projecting from the bottom and forwardly and rearwardly inclined surrounds the front and extends along the sides of each wheel.

I claim—

The ornamental design for a hydro-aeroplane body, substantially as shown and described.

EDSON F. GALLAUDET.
